UNITED STATES PATENT OFFICE.

HARRY J. LESCHEN, OF ST. LOUIS, MISSOURI, ASSIGNOR TO A. LESCHEN & SONS ROPE COMPANY, OF ST. LOUIS, MISSOURI, A CORPORATION.

DESIGN FOR A SIGN.

42,636.

Specification for Design.

Patented June 18, 1912.

Application filed January 18, 1912. Serial No. 671,997. Term of patent 14 years.

To all whom it may concern:

Be it known that I, HARRY J. LESCHEN, a citizen of the United States, residing at St. Louis, in the State of Missouri, have invented a new, original, and ornamental Design for Signs, of which the following is a specification, reference being had to the accompanying drawing, forming part thereof.

The figure is an elevation of a sign showing my new design.

I claim:

The ornamental design for a sign, as shown.

H. J. LESCHEN.

Witnesses:

A. J. McCauley,
E. B. Linn.
